UNITED STATES PATENT OFFICE.

ALFRED PAPILLON, OF MERMENTON, LOUISIANA.

DELIVERY-VALVE FOR CENTRIFUGAL PUMPS.

1,031,580.

Specification of Letters Patent.

Patented July 2, 1912.

Application filed June 8, 1904. Serial No. 211,622.

To all whom it may concern:

Be it known that I, ALFRED PAPILLON, a citizen of the United States, residing at Mermenton, in the parish of Acadia and State of Louisiana, have invented certain new and useful Improvements in Delivery Valves for Centrifugal Pumps; and I do hereby declare the following to be a full, clear, and exact description of the invention, such as will enable others skilled in the art to which it appertains to make and use the same.

This invention relates to improvements in centrifugal pumps, and more especially pertains to the delivery valve and its casing.

The object of the present invention is to provide a pump of the character mentioned embodying in its construction a novel and efficient form of removable seat for the delivery valve, whereby the priming of the pump is rendered absolutely certain and regular, and by which when the packing of the joints, in proximity to the seat, has become worn, such packing may be readily and quickly replaced.

With this general object in view, and others which will appear as the nature of the improvements is better understood, the invention consists substantially in the novel construction, combination and arrangement of parts as will be hereinafter fully described, illustrated in the accompanying drawings, and pointed out in the appended claims.

In the drawings—Figure 1 is a side elevation of a centrifugal pump provided with the herein-described invention, the delivery pipe thereof and the adjacent parts being shown in section. Fig. 2 is a sectional plan view of the delivery valve casing and valve on the line 2—2, Fig. 1, the valve being illustrated in closed position. Fig. 3 is an inverted plan view of the delivery valve casing. Fig. 4 is a transverse sectional view, on an enlarged scale, of the removable valve seat.

Referring to the drawings, the numeral 1 designates a centrifugal pump, which may be of ordinary construction and provided 50 with the inlet 2 and the outlet 3. The outlet 3 is flanged, as at 4, and bolted to said flange 4 is a bushing 5 having a lower flange 6 and an upper flange 7, said flanges being braced by longitudinally-extending struts 8 in order 55 to strengthen the same. Surmounting the bushing 5 is a delivery valve chamber 9, to

which a delivery pipe 10 is connected in any suitable manner, and said casing is flanged at its lower end, as at 11, whereby the same may be fixed to the upper flange 7 of the 60 bushing 5, a series of bolts 12 being employed for this purpose.

As before premised, it is one of the objects of the present invention to provide a removable seat for the delivery valve, the latter being designated by the numeral 13, and to this end an annular valve seat 14 is interposed between the flange 7 of the bushing 5 and the flange 11 of the casing 9, the opening of said valve seat corresponding in size to 70 the bore of the bushing 5 but being less than the diameter of the casing 9. The valve seat 14 is provided with an outer series of openings 15 through which openings the bolts 12 are passed to secure the valve seat in proper position upon the bushing 5, and said valve seat is also provided with an inner series of openings 16 surrounded by countersinks 17. The openings 16 and the countersinks 17 are designed to receive a series of rivets 80 18, which are pressed tightly in place in the valve seat, and interposed between the valve seat 14 and the flange 7 is a packing gasket 19. A similar gasket 20 is also arranged between the flange 11 of the casing 9 85 and the upper face of the seat 14, said gasket 20 being of the same width as the width of the seat 14 in order to effectually cover the upper surface thereof. The purpose of this gasket 20 is to afford a tight joint when the 90 delivery valve 13 is seated thereon, and this occurs when the pump is not working, the valve 13 being seated by gravity in an obvious manner. The gasket 20 is held in place by the rivets 18.

By referring to Fig. 3, it will be observed that the lower end of the casing 9 is provided with a flattened bearing surface 21 arranged at one of its sides, and the adjacent edge of the valve 13 is provided with a similar surface 22 designed to bear against the surface 21 when the valve is closed. Thus the valve 13 is limited in its downward movement, but not before the same is effectually seated upon the gasket 20 to form a 105 tight joint with the seat 14.

In order to effectually hinge the valve 13 within the casing 9, said valve is provided at its upper surface with parallel perforated ears 23 between which is fitted a perforated lug 24 carried by an attaching plate 25, which is located at the exterior of the casing

9, and which lug 24 projects through an opening in the casing 9 adjacent to the lower end thereof. The perforations of the lug 24 and the ears 23 register, and fitting within said perforations is a pivotal pin 26. The shank of the pin 26 forms the means whereby the valve 13 is hinged to the lug 24, and said pin is provided with a threaded neck 27, of enlarged diameter, which threaded neck is designed to enter a threaded opening 28 in the side of the casing 9 and be held therein to maintain the pin 26 in its proper relation to the valve 13. The pin 26 is also provided with a head 29 whereby the same may be rotated when it is desired to remove and replace said pin. This construction is clearly shown in Fig. 2. The casing 9 is also provided with a sight opening 30, whereby the valve 13 is visible from the exterior of the casing 9, and said opening 30 is closed by a covering plate 31 suitably held in position.

The pump 1 is also provided with a priming device 32, which priming device is preferably in the form of an ejector, the device 32 being connected to the casing of the pump and having its discharge pipe connected to the casing 9 so that upon operation the air exhausted from the casing of the pump 1 is projected into the delivery pipe.

The operation of the herein-described pump, after the same has been primed, is as usual, the body of water lifted by the pump and discharged through the outlet 3, forcing the valve 13 from its seat into the position shown by dotted lines in Fig. 1. So long as the pump continues to operate the valve remains in this position, but immediately upon the pump ceasing its operation the valve 13 gravitates to its closed position wherein the same is seated upon the gasket 20 carried by the seat 14. If at any time it is desired to remove the seat 14 the same may be readily

accomplished by simply withdrawing the bolts and raising the chamber 9 to permit the seat 14 being withdrawn, and if at any time the packing 20 should become worn to necessitate new packing being substituted therefor the same may be readily done in a similar manner. Whenever it is desired to examine the valve 13, without disconnecting the various parts, this may also be accomplished by removing the covering plate 31 to expose the opening 30, and through the latter the valve may be readily seen.

Having thus described the invention, what is claimed as new, and desired to be secured by Letters Patent, is:—

In a pump of the class described, the combination with the pump proper, and the delivery pipe thereof, of a casing interposed between the pump proper and said delivery pipe and communicating with the pump proper, a removable valve seat arranged between the casing and the pump proper and provided with an opening, said valve seat being displaceable in a direction laterally of said casing, a valve arranged in said casing and adapted to close upon said seat, a gasket arranged upon the face of the valve seat against which said valve closes, said seat having a series of countersunk holes around its opening, fastening devices arranged in said countersunk openings to hold the gasket around the opening of said seat, and detachable fastening devices passing through the edges of said casing and valve seat for removably holding the valve seat in position between the casing and the pump proper.

In testimony whereof I affix my signature, in the presence of two witnesses.

ALFRED PAPILLON.
